UNITED STATES PATENT OFFICE.

HERALD DICKERSON, OF ATLANTIC CITY, NEW JERSEY.

SAFETY-ENVELOP AND FASTENING DEVICE THEREFOR.

1,229,048.

Specification of Letters Patent.

Patented June 5, 1917.

Application filed September 6, 1916. Serial No. 118,760.

To all whom it may concern:

Be it known that I, HERALD DICKERSON, a citizen of the United States, residing at Atlantic City, in the county of Atlantic and 5 State of New Jersey, have invented new and useful Improvements in Safety-Envelops and Fastening Devices Therefor, of which the following is a specification.

This invention is an improved safety envelop and clasp for fastening the same, the 10 object of the invention being to provide an improved envelop of this kind which may be very readily sealed and fastened and which when fastened cannot be opened without injuring the envelop to such an extent as to betray the fact that it has been opened; another object being to provide an envelop 15 of this kind which is sealed without the use of mucilage and hence cannot be opened by first being steamed; another object being to provide an improved clasp for fastening and sealing the envelop and which is entirely covered by parts of the envelop when 20 the latter is fastened so that the clasp is entirely concealed.

The invention consists in the features of construction, combination, and arrangement of devices, hereinafter fully described and claimed.

30 In the accompanying drawings:

Figure 1 is a perspective view of a safety envelop constructed and arranged in accordance with my invention showing the same with the back disconnected from the 35 end flaps and with the sealing flap open.

Fig. 2 is a plan of the blank from which the envelop is made.

Fig. 3 is a vertical sectional view of the envelop partly opened and about to be 40 closed and sealed.

Fig. 4 is a similar view showing the envelop closed and sealed.

Figs. 5 and 6 are detail perspective views of the members of the clasp.

45 The blank A from which the envelop is formed is cut to provide a front 1, a back 2, end flaps 3 and a sealing flap 4. The end flaps are provided with extensions 5 to reinforce the envelop and the back is secured to the end flaps and their extensions by a mucilage as at 6. The sealing flap is formed with an inner fold 7 at its free edge and which is folded inwardly thereon, on the line 8 and an inner flap 9 is formed at the 50 free edge of the inner fold and which is folded thereon on the line 10. The inner

fold and the inner flap form extensions of the sealing flap.

To close the envelop, the inner fold is inserted between the front and the back as 60 shown in Figs. 3 and 4 and the sealing flap is then pressed against the back to cause its inner fold to bear directly against the back, the back being hence arranged between the inner flap and the inner fold. 65

To secure and seal the envelop, I provide a clasp which comprises a pair of members 11, 12. Preferably, the members of the clasp are made of sheet metal but may be made of any suitable material within the scope of 70 the invention. The clasp member 11, is secured on the inner side of the inner fold by means of points 13 with which said member is provided, said points being pressed through and clenched on the inner fold, 75 said member has also a headed stud 13' which projects through the inner fold and is adapted to be forced through the back and the inner flap.

The clasp member 12 is secured to the 80 inner side of the inner flap by points 14 which are forced through and clenched on the inner flap and said member has an opening 15, through which the head of the stud projects, when the envelop is closed. The 85 member 12 also has a sealing tongue 16 formed therewith and which is bent inwardly thereover and is also initially bent as at 17 and is provided at its free end with a notch 18. When the envelop is closed and 90 the head of the stud of the member 11 is forced through the back and inner flap and projects through the opening 15 of the member 12, the sealing tongue is then strengthened by pressure and hence its notched end 95 is caused to engage the shank of the stud and under the head of the stud, thus securely locking the two members of the clasp together and thereby effectually fastening and sealing the envelop. The parts of the 100 clasp are concealed in the envelop, entirely hidden from view and hence cannot be detached from each other excepting by first slitting the envelop and thus betraying the fact. Any suitable number of the clasps 105 may be used on the envelop, according to the size of the latter and the desired strength thereof, the envelop here illustrated is shown provided with two of my fastening clasps.

From the foregoing description, taken in 110 connection with the accompanying drawings, the advantages of construction and of

the method of operation will be readily apparent to those skilled in the art to which the invention relates, and while I have described the principles of operation of the device together with the device which I now consider to be the best embodiment thereof, I desire to have it understood that the device shown is merely illustrative and that such changes may be made when desired as are within the scope of the appended claim.

Having described the invention, what is claimed is:

A safety envelop comprising a front, a back, end flaps secured to the back, a sealing flap, an inner fold, an inner flap, said inner fold and inner flap forming extensions of the sealing flap and being adapted to be

arranged respectively on the outer side of the back and between the back and the front when the envelop is closed, and a clasp to fasten the inner fold, back, and inner flap together and thereby seal the envelop, said clasp comprising a pair of members respectively secured to the inner fold and inner flap, one of said members having a headed stud and the other having an opening to receive the stud and being also provided with a sealing tongue bent thereover, having a notch in its outer end and being adapted when straightened to engage said notched end under the head of the stud.

In testimony whereof I affix my signature.

HERALD DICKERSON.
